UNITED STATES PATENT OFFICE.

GORDON C. GREEN, OF SWIFT CURRENT, SASKATCHEWAN, CANADA.

CORSET-FASTENER.

1,307,667.

Specification of Letters Patent. Patented June 24, 1919.

Application filed February 17, 1919. Serial No. 277,408.

To all whom it may concern:

Be it known that I, GORDON C. GREEN, a subject of the King of Great Britain, residing at Swift Current, Province of Saskatchewan, Canada, have invented certain new and useful Improvements in Corset-Fasteners, of which the following is a specification.

My invention relates to a device for fastening corsets quickly and in a most effective manner. My invention comprises an implement or hook, preferably formed of a single integral piece of metal, so arranged and proportioned as to be adapted to be inserted through the eye of the corset and into engagement with the post and thereafter to be swung in a horizontal plane so as to position the eye over the post with the utmost expedition and certainty. It is especially adapted for use in connection with the standard metal eyes and hooks now used on corsets, in which the eye has a curved opening therein terminating in an elongated slot. The end and shank portions of my improved device are adapted to be extended through and to closely engage within this slot portion of the metallic eye, so that the motion of the hook is guided and controlled by such engagement. The shank portion of my device is so curved as to cause the eye of the corset to slide easily over the same and inwardly toward the body of the wearer when the hook is operatively positioned and is swung across the body of the wearer as stated, as opposed to the operation of an implement having a straight shank in which the operative swinging movement would tend to force the edge of the corset carrying the eye away from the body and to cause sticking of the same on the shank. The operative end of the shank comprises a short portion which extends at an angle to the shank, is provided with a recess to engage the head of the post, when the device is first positioned, and a notch in its extreme end to engage the shank of the post during the subsequent pivotal movement of the device. For the best results, the face of the operative end opposite to that in which the recess referred to is positioned should be given an inclination which is substantially parallel to the axis of the handle portion of the device.

I am aware of the fact that implements have previously been devised for buttoning gloves, collars, shoes, etc., having some of the features of my device. These hooks, however, are so far as I am aware all adapt-

ed to button a flexible fabric button hole over a fixed button or post, this constituting a distinctly different problem from the one involved in fastening an inflexible metal eye over a post. The flexibility or adjustability, which in the first case is provided by the flexible member containing the button hole, must in the second case be provided by the exact form and relation of parts of the fastener, and in my invention I have so proportioned and correlated the various parts as to produce the desired effect.

In order that a clearer understanding of my invention may be had, attention is hereby directed to the accompanying drawings forming part of this application and illustrating certain embodiments of my invention. In the drawings, Figure 1 represents a front elevation of my improved device operatively positioned through a metal eye and into engagement with the post of a corset; Fig. 2 is a top plan view of the device so positioned; Fig. 3 is a partial top plan view of the device toward the end of its operative movement; Fig. 4 is a plan view of my improved implement viewed from the opposite side to that shown in Fig. 1; Fig. 5 is a side elevation of the same; Fig. 6 is an enlarged partial plan view of the operative end of the device; and Fig. 7 is a section taken on line 7—7 of Fig. 6.

Referring to the drawings, the fastener comprises a metal strip having a handle portion 1 with shank portion 2 and an operating end portion 3 at the end of the shank. The handle portion preferably takes the form of a loop which is offset from the shank portion, as shown, in the direction of the width of the fastener, this handle portion being adapted to form a firm and convenient grip for the device and also to constitute an enlargement which cannot possibly be inserted through the eye of the corset.

The shank and operating end portions 2 and 3 are preferably of a uniform width, as is shown in Figs. 1 and 4, adapted to extend through and closely fit within the slot portion of the eye of the corset. In the direction transverse to its width the shank portion is gently curved in the manner indicated at 4. The operating end portion is offset slightly from the shank portion, as by suitably cutting away the end of the latter. It is provided with a short face 5 which preferably is approximately parallel to the axis of the handle portion 1. This face 5 may be

formed by cutting or grinding the end of the shank portion 2. On its opposite face the material at the end of the shank portion is cut back to form the slanting surface 6, and the face 7 which is substantially parallel to the opposite face 5. The end surface of the operating end portion is provided with a curved notch, as is indicated at 8. A shallow recess 9, which may be of a more or less circular shape, is provided on the face 7 immediately to the rear of the notched end 8, the slanting surface 6 rising from the recess 9.

The device is illustrated as being operatively positioned in Figs. 1, 2 and 3, in which it will be noted that the operative end and the shank portion of the device are inserted through the opening 10 of one of the metal eyes 11 secured to one of the steels 12 of the corset indicated at 12'. The eye 11 is represented as being one of the standard metal eyes which are now used on all kinds and makes of corsets, the opening 10 of the eye having a forwardly directed slot portion 13. It will be observed that the width of the end and shank portions is just sufficient to enable the same to closely fit within and slide through the slot portion 13 of the eye.

The other steel 14 is illustrated as provided with one of the standard metal corset posts having a shank portion 15 and a head 16, it being understood that the steels 12 and 14 are provided with vertical rows of eyes and posts. The end and shank of the implement being inserted through the slot of the eye as stated, the recess 9 of the operating end is engaged with the head 16 of a post and the implement is then swung in a horizontal plane about the post as a fulcrum, the device swinging away from the body of the wearer and then toward the body, the notched end 8 engaging the shank 15 of the post as the handle of the device moves toward the left side of the body, at the completion of the movement. During this movement the curvature 4 of the shank aids the eye 11 to slide easily over the shank and toward the body of the wearer, so that at the completion of the movement the post will be inserted through the opening of the eye and the device disengaged. It is to be particularly noted that the curvature 4 is so chosen as to cause the eye to move inwardly toward the body as it is moved forwardly toward the steel 14 during the entire movement, and also that the close engagement of the shank within the slot 13 of the eye guides the shank and tends to hold the device in the desired plane during the movement. The curvature 4 of the shank was chosen as the result of experiment, the curvature shown in the drawing being substantially that which is believed to be the best adapted for the purpose. The provision of the plane surface 5 on the under side of the operative

end, in substantial parallelism with the handle portion 1, insures the possibility of swinging the handle toward the body at the end of the operation and the certain disengagement of the operative end from the eye at the completion of the fastening movement. It will also be noted that the operating end of the device is readily formed on the end of the shank portion, as by cutting away some of the material of the same, and is of what may be termed a skeleton form, no more metal being provided than is essential for its operation in connection with the post. It will also be noted that whereas in the case of buttoners for gloves, collars and the like, the flexibility of the fabric in which the button hole is formed provides sufficient "give" to enable devices of various shapes and proportions to be used, the inflexibility and rigid character of the metal eyes of a corset present a problem which must be specially considered, and my improved implement is devised especially for the purpose of solving this special problem in the most effective way.

In buttoning the corset it is preferable to begin at the bottom, using my device as explained above, the various eyes being fastened over the corresponding posts with great rapidity and a minimum of effort. This operation of fastening the eyes over the posts by the use of my device is preferable to the method in which the garment is fastened and unfastened by adjustment of the laces, because it may be performed much more quickly, and also for the reason that the garment having once been fitted to the wearer, the laces may be left at the desired adjustment and the corset fitted to exactly the same shape each time, by the use of my device, whereas if the adjustment is made by lacing and unlacing, it is apt to be too tight one time and too loose the next.

What I claim is:—

1. A corset fastener having a handle portion and shank portion, the latter terminating in an operating end portion, said shank portion and end portion being proportioned to extend through and said shank portion to closely fit within the slot portion of a standard metal corset eye, when operatively positioned, said end portion extending at an angle to said shank portion, having a recess to engage the head of a corset post and a notched end to engage the shank of the post, and said shank portion being so curved as to cause the eye to slide easily over the same, toward the post and inwardly toward the body of the wearer, when the fastener is operatively positioned and is swung horizontally across the body.

2. A corset fastener formed of a strip of metal having a handle portion and shank portion, the latter terminating in an operating end portion, said shank portion and end

- portion having a uniform width such that the same will extend through and closely fit within the slot portion of a standard metal corset eye, when operatively positioned, said 5 end portion having a face extending at an angle approximately parallel to the axis of the handle portion, and having an opposite face adapted to engage the head of a corset post, and a notched end adapted to engage 10 the shank of the post, and said shank portion being so curved in a direction transverse to its width as to cause the eye to slide easily over the same, toward the post and inwardly toward the wearer, when the fastener is operated. 15
3. A corset fastener formed of a strip of metal having a handle portion and shank portion, the latter terminating in an operating end portion, said shank portion and end 20 portion being adapted to extend through the slot portion of a standard metal corset eye, when operatively positioned, said shank portion being so curved as to cause the eye to slide easily over the same, toward a corset post and inwardly toward the body of the 25 wearer, when the fastener is operatively swung across the body of the wearer, and said end portion having an end and a face adapted to engage a corset post, and an opposite face, extending at an angle to the shank portion and substantially parallel to the handle portion, adapted to allow the corset eye to disengage from the corset fastener. 30

This specification signed and witnessed this 10th day of February, 1919.
